UNITED STATES PATENT OFFICE.

DANIEL L. EUSTICE, OF GALENA, ILLINOIS.

PACKING-MACHINE.

SPECIFICATION forming part of Letters Patent No. 784,932, dated March 14, 1905.

Application filed November 24, 1903. Serial No. 182,468.

To all whom it may concern:

Be it known that I, DANIEL L. EUSTICE, a citizen of the United States, residing at Galena, in the county of Jo Daviess and State of Illinois, have invented new and useful Improvements in Packing-Machines, of which the following is a specification.

My present invention is an improvement over an invention shown in an application filed 10 by me on the 15th day of July, 1903, and numbered 165,700; and the improvement consists mainly in the table and in the mode of applying the power to operate the table.

It further consists in giving peculiar movements to the table whereby the table may be made to start slowly, then move rapidly, and then brought slowly to a standstill, or other convenient movements may be given to the table to accommodate it to different varieties 20 of material or liquids to be packed and different movement necessary to carry out the design of the machine.

The following specification, when taken in connection with the drawings accompanying 25 the same and forming a part hereof, will give in detail the manner in which it is constructed and the mode of its operation.

Figure 1 shows a perspective view from one side of the machine. Fig. 2 is a perspective 30 view from the opposite side of Fig. 1, showing part of the traveling tables and frame cut away to show the weighing mechanism and the device for bringing the tables into gear. Fig. 3 is a perspective view showing the mode 35 of advancing the tables and of giving them a variable movement. Fig. 4 is a perspective view of one of the shafts for operating the table with the plates on top of the shaft and its connection with the weighing and feeding 40 mechanism. Fig. 5 is a perspective view taken from the opposite side of Fig. 4 and showing means for operating the other table. Fig. 6 is a perspective view of one set of the plates mounted upon one of the operating-shafts and 45 showing the arm in the groove and the locking-pin raised. Fig. 7 is a perspective view of the outer tube of the feeding mechanism. Fig. 8 is a longitudinal section of the feeding mechanism. Fig. 9 is a perspective view of 50 the inner tube of the feeding mechanism and

showing the inlet and discharge openings. Fig. 10 is a perspective view of the locking-pin. Fig. 11 is a perspective view of the gears for advancing the table at a variable rate of speed. Fig. 12 is a plan view of one 55 of the plates comprising the table. Fig. 13 is a perspective view of a modification of Fig. 12. Fig. 14 is a transverse section of the endless tables and their supporting means.

Referring to the drawings, the frame, which 60 consists of two side bars 2, one on each side of the tables, is secured to standards 4. The side bars 2 are stayed at intervals by cross-bars 3, as seen in Fig. 14, disposed at right angles to the side bars beneath the tables and 65 to which the side bars are also fastened. Along on the top of each side bar 2 is secured a metal strip 5, and in the center between the side bars 2 is an inverted-T-shaped strip 6, rigidly secured to the cross-bars 3, and upon 70 these strips 5 and 6 the endless tables presently to be described travel.

The tables 8 and 10 consist of plates or links 12, provided with openings 13 near their center, which plates are hinged or linked together 75 by forming a slot 14 in one end of the plate and upon the other end a hook 15, adapted to engage in the slot 14 of a contiguous plate. These plates when united together form an 80 endless flexible table. There are grooves 11 around the holes 13 for determining the position the package is to occupy when it is being filled.

When it is desired to fill two or more cans at the same time and with one weighing mechanism, using only a single table, these plates or links 12 are widened out, as shown in Fig. 13. They would still have but one opening 13 therethrough; but this opening 13 would be in one side, and a space 9 at one side of the 85 link on which the other cans to be filled are set. There may be a groove 11 in the plate for convenience in determining where the can shall be set. In this manner all the cans upon any plate may be filled at the same time. In 90 Fig. 13 I have shown only plates for two cans; but it is manifest that the plates may be wide and long enough to sustain a number at the same time.

At one end of the frame is journaled in the 100

side bars and standards 4 a shaft 16, and upon this shaft are loosely mounted sprocket-wheels 18, one for each table, which wheels are each provided with sprockets 20 set the same distance apart as the distance between the openings 13 in the plates, so that the sprockets will engage the openings in the plates. It is not necessary that these be sprocket-wheels, as it is manifest that they may be drums or any other convenient arrangement for the tables to travel over. At the opposite end of the machine are journaled two shafts 21 and 22 in the side bars 2 and standards, and on the shaft 22 is rigidly mounted a sprocket-wheel 24, the sprockets 20 of which engage the openings 13 in the table 10 and advance the same when power is applied to the sprocket-wheel 24. On the shaft 21 is rigidly mounted another similar sprocket-wheel 25, having sprockets 20 adapted to engage the openings 13 in the plates which form the table 8 and advance said table.

For the purpose of advancing the tables there is secured upon a platform 26 bearings 25 or standards 28, in which a shaft 30 is set to rotate. The outer ends of this shaft 30 are provided with worm-gears 32 and 33. Through the platform 26 near the worm-gear 32 is set a shaft 34 and near the gear 33 another shaft 35.

Upon the top of the shaft 34 is rigidly secured a circular plate 36 and on the shaft 35 a similar plate 38. These plates are each provided with a groove 40. On the shafts 34 and 35 below the plates 36 and 38 are loosely mounted plates 41 and 42, each provided with a gear 44. These plates are also provided with one or more notches or recesses 45. The plates 36 and 38 are recessed out, and in each of said recesses is loosely inserted a rectangular-shaped pin 46, (shown in Fig. 10,) in which is a recess 48. Said pin is adapted to engage the recesses 45 in the plates 41 and 42. On the top of each of the plates 36 and 38 is placed a spring 50, adapted to rest on a pin 46 and hold it in engagement with one of the recesses 45 in the plates 41 and 42. Upon the shaft 30 is mounted a pulley 51, which is belted to the power by a belt 52.

Upon the lower end of each of the shafts 34 and 35 beneath the platform 26 is secured a gear 55. (Shown in Fig. 11.) This gear is of oblong or elliptical shape and is mounted upon its shaft near one end and adapted to mesh in with a gear 56 of substantially the same shape. The gears 56 are mounted upon shafts 58 and 60 in the same manner that the gears 55 are mounted on the shafts 34 and 35.

To each of the shafts 58 and 60 are secured bevel-gears 61, (shown on shaft 60,) which mesh into gear-wheels 62 and 63, the gear-wheel 62 being mounted upon the shaft 21, which rotates the sprocket-wheel 25 and advances the table 8 and the gear-wheel 63 upon the shaft 22, which rotates the sprocket-wheel 24 and advances the table 10. On the plat-

form 26 is also secured a standard 64, and in the top of said standard is pivoted an arm 65 of chisel shape at the end 66 and provided with a pin 68, set on top near the middle of the arm. There are two of these standards, 70 one near each plate 36 and 38, so set on the platform that the arms 65 will engage the grooves 40 in the plates 36 and 38. For the purpose of holding these arms in engagement with the grooves 40 there is secured to each arm a coil-spring 70, attached at the other end to a post 72.

The weighing mechanism consists of a platform 75, upon which are set two uprights or standards 76. These standards are connected 80 together by a bar 78, and to this bar are pivoted balance-beams 79 and 80. To the beam 79 is attached a weight 81, and to the beam 80 is a weight 82. To the outer end of the beam 79 is secured a bar 84, upon the top of 85 which is a platform 85. The beam 80 has upon its outer end a like bar 86, upon the top of which is a platform 87. To the standards 76 are also pivoted two bars 88 and 89. To the bar 88 is pivoted a bar 90, loosely attached 90 to the base of the bar 84, and to the bar 89 is attached a similar bar which is adapted to loosely engage the bar 86 at the opposite end of the platform 87.

In order to apply the power and bring the 95 gears which advance the tables into operative engagement and to operate the feeding or filling cut-off at the same time, there is attached to the bar 86 an arm 92, which projects forward and engages a loop 93, and upon the bar 100 84 is attached an arm 94, which also projects forward and engages a loop 95. Within the traveling tables there is hung a platform 96 by hangers 98, attached to the side pieces 2. Upon this platform are two standards 99, in 105 which is journaled a shaft 100 and on which are secured two ratchet-wheels 101. Upon the same platform are set two other journal-bearings 102, in which is journaled a shaft 103. On the shaft 103 is rigidly fastened near 110 one end an arm 104, to the outer end of which is pivoted an arm 105, terminating in a hook or ratchet 106, adapted to engage a ratchet-wheel 101 on the shaft 100. On said shaft 103 is loosely mounted a sleeve 110, to which is 115 secured an arm 108. To the outer end of this arm is pivoted an arm 112, carrying a hook or ratchet 114, adapted to engage one of the ratchet-wheels 101 on the shaft 100. The arm 105 carries the loop 93, and the arm 112 carries the loop 95.

The sleeve 110 is provided with a lug or arm 115, to which is pivoted a bar 116, that extends backward and is pivoted to a crank 118, pivoted near the top of the standard 99. 125 Upon the outer end of the shaft 103 there is secured a lug 120, which is attached to the crank 118 by a bar 122.

It will be observed that as the arm 108 is attached to a sleeve upon the shaft 103 and 130

the outer end of said shaft is attached to the 5 crank 118 by the rod 122 and the sleeve is attached to the same crank 118 by the rod 116 and as the arm 104 is rigid on the shaft 103 when this arm is drawn forward by the rotation of the wheel 101 the same movement will draw back the arm 108, as shown in Fig. 2.

Upon the shaft 100 on the outside of the 10 frame is secured a sprocket-wheel 124, which is belted by a sprocket-belt 125 to a sprocket-wheel 126, set upon a shaft 127, and is preferably operated by the power which operates the feeding mechanism.

Upon the outer end of the shaft 103 is 15 mounted a circular plate 128, provided with two notches 130 131, with which a spring-hook 132 is adapted to engage. At the outer end of the shaft 103 is secured an arm 133, and to the end of this arm is loosely attached 20 a tube 134, into which a rod 135 telescopes for adjustment in length and is held in the required adjustment by a set-screw 136. This rod 135 is loosely attached to an arm 138, which is secured to a shaft 140, attached to the end 25 of the cut-off of the feeding mechanism presently to be described. In the end of the shaft 140 are two pins 141 and 142, set on opposite sides from each other on a plate 143.

For the purpose of operating the feeding 30 mechanism whereby the flow of the axle-grease or other filling material is cut off from filling one can upon one table and open to fill the can on the other table there is attached to the standard 72 a coil-spring 144, to which 35 is loosely secured a bar 145, provided with a notch 146, adapted to engage the pin 68 upon the arm 65, which engages the groove 40 in the plate 36. The outer end of the bar 145 is loosely attached to a swinging standard 148, 40 pivoted to the platform 26 by the pivot-pin 149. There is attached to the bar 148 a cord or rope 150, which is secured at its other end to a pin 142 on the plate 143.

To the standard 152 is attached a coil-spring 45 153 and a similar bar 154, attached to the standard 155, pivoted in the platform 26. The bar 154 is provided with a notch (not shown, but the same as notch 146) adapted to engage the pin 68 upon the arm 65, which engages 50 with the slot 40 in the plate 38. To this standard 155 there is attached a cord 156, which is connected to a pin 141 upon the plate 143.

For the purpose of aiding in operating the 55 weighing mechanism and to hold down the platform 85 while the table is advanced there is secured on the shaft 58 a circular plate 158, provided with a rim in which is a rounded notch or depression 159.

A rod 162 is pivoted in a bearing 163 and 60 provided with an arm 164, adapted to engage the under edge of the rim and enter the notch 159. The rod 162 extends underneath the table to the opposite side of the frame, passing through bearing 165. Near the end of this 65 bar 162 is attached an arm 166. This arm is

connected by a bar 168 to an arm 170, hinged to a hanger 171. The outer end of the arm 170 rests upon the arm 90. It will be seen that when the plate 158 is rotated by the shaft 58 the bar 162 will be partially rotated by the 70 engagement of its arm with the plate 158 when the arm enters the notch 159, and this will draw down upon the arm 90 and hold the platform 85 down while the table is advanced. Then when the arm is forced out of the notch 75 by the rotation of the plate 158 the arm 90 will be released.

To the shaft 60 is attached a plate 168, similar to the plate 158. This is connected by a bar 172 to the arm 174, which bears upon 80 the arm 91 to hold down the platform 87 while the table 10 is traveling, the same as the platform 85 is held down by the arm 170. To this bar 172 is attached an arm 173, adapted to engage the notch 171 in the plate 168. 85

The filling or feeding mechanism may be of any convenient construction, such as shown in my above-mentioned application. A simple device for use in filling cans with liquids in this machine is shown in Figs. 7, 8, and 9 and 90 consists of a supply-tank 175. Beneath this tank is set a tube 178, which is connected to the tank by a tube 180. Within the tube may be arranged an ordinary valve for the purpose of controlling the supply of the filling 95 material. This tube 178 is provided on its under side with two discharge-openings 181 and 182. Within this tube is placed another tube 184. To the forward end of the tube 184 there is secured a cap 185, which is of 100 sufficient thickness to form a shoulder 186, against which the tube 178 contacts and prevents the inner tube from further entrance into the tube 178. The other end of the tube 184 is provided with a similar cap 188, to 105 which is secured the shaft 140 for partially rotating the tube 184. The tube 184 is also provided with an inlet-opening, but it is of double the size of the inlet from the tank and coincident with said inlet, so that when the inner tube is partly rotated the opening will 110 still be coincident with the inlet from the tank and outer tube. The tube 184 is also provided with two discharge-openings 190 and 191, formed at the same distance from the rear 115 end that the openings 181 and 182 are from the same end of the tube 178, the openings 190 arranged to discharge the contents of the tube 184 through the openings 181 and the opening 191 through the opening 182. The 120 openings 190 and 191 are not in alinement with each other, but the openings 181 and 182 in the tube 178 may be. It will be seen by this mode of construction that the material to be packed will pass from the tank through 125 a valve in the tube 180 into the tube 184, and when the tube 184 is partially rotated till the opening 190 is coincident with the opening 181 the material will be discharged into a can placed upon one of the tables, and when 130

the opening 191 is coincident with the opening 182 it will discharge it into another can placed upon another table.

The mode of operating my device is substantially as follows: Power is applied to the belt 52, which operates the pulley 51 and the shaft 30, and as the worm-gears 32 and 33 are attached to the outer ends of the shaft 30 and also engage the gears 44 upon the plates 41 and 42 the rotation of the shaft 30 will rotate the plates 41 and 42, and when the pins 46 are in engagement with the plates 41 and 42 they will both be rotated and at the same time rotate the shafts 34 and 35 and gears 55 and 56, which will also rotate the shafts 58 and 60. Since the shafts 58 and 60 are in engagement with the wheels 62 and 63 on the shafts 21 and 22, the shafts 21 and 22 will be rotated. They in turn will rotate the sprocket-wheels 24 and 25 and advance the tables 8 and 10, but not at the same time, from the fact that the arm 65 does not engage the groove 40 in the plate 36 at the same time that the similar arm 65 engages the groove 40 in the plate 38. The locking-pin 46 does not lock the plates 36 and 41 at the same time that a similar pin 46 locks the plates 38 and 42, and hence while one set of the plates 36 and 41 are being rotated there will be no rotation of the plates 38 and 42. Therefore when the table 10 is in motion the table 8 ceases to move and cannot move until the table 10 has ceased to move. The cans to be filled are then placed over the holes 13 on both tables, and as one of the tables advances a can will be drawn along until it comes to the place where the platform 85 is arranged to pass up through one of these openings 13. The table 8 then has ceased its motion, because the arm 65 has entered the groove 40 in the plate 36 and has raised the pin 46 out of engagement with the holes 45 in the plate 41, and hence the plate 36 has ceased to rotate, which stops the rotation of the sprocket-wheel 25, which advances the table 8. The table 8 will not move again until after the can is filled, as the spring 70 holds the arm 65 in engagement with the groove 40, and the arm is not released from engagement with the groove until after certain operations are performed by other parts of the machinery caused by the filling of the can to such an amount as to force down the platform 85. When the can is filled till the contents are equal to the weight 81, it will force down the platform 85, and at the same time the arm 94 will also move down in the loop 95 and permit the arm 112 to fall by its own gravity till the ratchet 114 engages the ratchet-wheel 101 on the shaft 100, and as the ratchet-wheel is continually in rotation the ratchet-wheel will draw forward the arm 108, and the sleeve 110 will force back the connecting-rod 116 and partially rotate the shaft 103 until the catch 131 on the spring-arm 132 has engaged 65 in another notch 130 on the wheel 128. This

partial rotation of the wheel 128 will turn the arm 133, drawing down the tube 134, and with it the rod 135, which will slightly turn the arm 138 and partially rotate the shaft 140 and cut off the flow of the filling material into the can through the opening 190 in the tube 184 and the opening 181 in the tube 178 and turn it into a can resting upon the table 10 over the platform 87 through the openings 191 and 182. The rotation of this shaft 140 will draw the cord or connection-chain 150 and pull forward the standard 148, and with it the bar 145, and as the pin 68, which is attached to the arm 65, is in engagement with the notch 146 in the bar 145 when this bar is drawn backward it will pull the arm 65 out of engagement with the groove 40 in the plate 36 and allow the pin 46 to be forced down by the spring 50 into engagement with one of the openings 45 in the plate 41, and this will cause the shaft 34 to again rotate and by its connection with the sprocket-wheel 25 will advance the table 8 till the plate 36 has rotated sufficiently to have the lug 67 come in contact with the bar 145 and release the pin 68 from engagement with the notch 146, which will allow the spring 70 to come into action and draw the arm 65 into engagement with the groove 40 in the plate 36, and thereby raise the pin 46 out of engagement with the plate 41, and the shaft 34 will cease to rotate, and the sprocket-wheel 25, with the table 8, will have come to a standstill. At this time the arm 164 upon the rod 162 has come into engagement with the notch 159 in the circular plate 158, and said rod 162 has been partially rotated, turning the arm 166 and bringing down the arm 170 upon the arm 90, holding it down in that position, where it will remain until after the table 8 has been moved. At this time the filling device has commenced to fill a can placed upon the table 10 over the platform 87, which now projects up through one of the holes 13 and sustains the can. As soon as it is filled to the amount of the weight 82 the platform 87 will be forced down, and with it the arm 92, within the loop 93 and permit the arm 105 to fall by its own gravity and the ratchet 106 to engage the ratchet-wheel 101 on the shaft 100. It will draw forward the arm 105 and also the arm 104 and rotate the shaft 103, which will at the same time rotate backward the wheel 128 in the opposite direction into the notch 131. This will raise the arm 133 and force up the tube 134 with the rod 135 and partly rotate the shaft 140 and change the flow of material into a can on the adjoining table. It will also draw back the post 155, and with it the bar 154, and bring the arm 65 out of engagement with the groove 40 in the plate 38 and allow a pin 46 to be forced into one of the openings 45 in the plate 42, and this action will commence to rotate the shafts 35 and 60 and the shaft 22, with the sprocket-wheel 24, and advance the table 10. It will be seen

that only one of these tables can be advanced at the same time, and neither table advances while any one of the platforms is above the surfaces of the tables.

5 In order to control the movements of the tables and start them slowly, then increase their speed, then bring them slowly to a standstill, so that there shall be no sudden start to spill out the liquid that may be in a can when 10 filled, there is arranged upon the shaft 34 a gear 55 of nearly an ellipse shape, as shown in Fig. 11. Meshing in with this is another gear 56 of similar shape, which is mounted upon the shaft 58 near one end of the gear 15 56. The shaft 58 operates the table 8. The mode in which these two gears 55 and 56 operate to give motion to the table is substantially as follows: When the portion of the gear 55 engages the gear 56 at the farthest 20 distance from the shaft 34, it will turn the gear 56 more rapidly than one nearest to the shaft, and the table commences to move when the gear 55 is in engagement with the gear 56 nearest to the shaft 34, and when the table 25 stops it will be in the same position, having traveled once around. Hence the table will be given a very slow movement at starting and gradually increasing to a rapid movement and decreasing slowly till it ceases to move. 30 In this manner there will be no sudden jerks of the can to displace it from the platform or to disturb the contents if a liquid.

It will be observed that each table is moved separate and independent of the other tables 35 and each given an intermittent movement or what may be termed a "progressive" step-by-step feed and at a variable speed, starting slowly, then increasing to a rapid movement, and then ending with a slow movement. It 40 will further be seen that tables are advanced alternatively, and the construction is such that one table after it has removed a package from the filling mechanism the distance between two openings in the table cannot 45 not move farther till after the other table has also forwarded a filled package the same distance.

Having now described my invention, what I claim is—

50 1. In a package-filling machine, a filling mechanism, an endless flexible traveling table, a weighing mechanism inclosed by the table and means connected with the weighing mechanism for controlling the movements of 55 the table and preventing any movement of the table while the filling mechanism is operating to fill a package.

2. In a package-filling machine, a traveling table consisting of plates loosely united together to form an endless flexible table, a weighing mechanism, and means actuated by a filled can and connected to the weighing mechanisms for applying power to advance the table.

65 3. In a package-filling machine, an endless

flexible traveling table, a weighing mechanism inclosed by the table, and means for automatically advancing the table by an intermittent motion.

4. In a package-filling machine, a traveling 70 table formed of plates flexibly united together and provided with openings in the plates, a sprocket-wheel for advancing the table adapted to engage the openings in the plates, means for rotating the sprocket-wheel, and a weighing mechanism having a platform adapted to be projected and retracted through the openings in the table.

5. In a package-filling machine, a flexible traveling table provided with openings therethrough, a weighing mechanism having a platform adapted to be raised through the openings in the table, means for lowering and withdrawing the platform through the openings in the table and means for automatically applying power to operate the table.

6. In a package-filling machine, an endless flexible traveling table, a weighing mechanism inclosed by the table and means connected with the weighing mechanism for automatically applying power for advancing the table.

7. In a package-filling machine, an endless flexible table, a sprocket-wheel to advance the table, a weighing mechanism inclosed by the table, a filling mechanism and means operated 95 by the filling mechanism and connected with the weighing mechanism for rotating the sprocket-wheel to advance the table.

8. In a package-filling machine, an endless flexible traveling table provided with openings, a weighing mechanism provided with a balance-beam, a platform attached to the balance-beam and adapted to be raised through the openings in the table, means for lowering the platform through the openings in the table, means for advancing the table, and connection between the weighing mechanism and the means for advancing the table.

9. In a package-filling machine, an endless traveling table provided with openings therethrough, a weighing mechanism having a platform connected with the balance-beam of the weighing mechanism and adapted to be raised through the openings in the table, means for lowering the platform through the openings in the table and means engaging the balance-beam for applying power to operate the table at a variable rate of speed.

10. In a package-filling machine, a traveling table, intermittently-operated mechanism for imparting a progressive step-by-step feed to the table, a weighing mechanism operated by the filled package to energize said intermittently-operated mechanism, and a filling mechanism operated by the weighing mechanism 115 synchronously with the energizing of the intermittently-operated mechanism.

11. In a package-filling machine, a traveling table, a weighing mechanism and means connected with the weighing mechanism for ad- 130

vancing the table consisting of a rotating ratchet-wheel a ratchet attached to a shaft adapted to engage said ratchet-wheel a driving-shaft, and connection between the driving-shaft and the ratchet-wheel shaft.

12. In a package-filling machine, an endless traveling table, a feeding mechanism, a weighing mechanism and means connected with the weighing mechanism to apply the power to operate the table consisting of a shaft provided with a ratchet-wheel a shaft 103 and connections between the shaft and the power-operated mechanism.

13. In a package-filling machine, a traveling table, a filling mechanism, a weighing mechanism and connection between the weighing mechanism and the filling mechanism for operating the filling mechanism, and means including said connections for advancing the table intermittently and at a variable speed.

14. In a package-filling machine, a traveling table, a filling mechanism, a weighing mechanism and connection between the weighing mechanism and the table for advancing the table intermittently and at a variable speed.

15. In a package-filling machine, a traveling table provided with openings, a filling mechanism, a weighing mechanism operated by the filled can, connection between the weighing mechanism and filling mechanism for operating the filling mechanism, means connected with the filling mechanism operated by the weighing mechanism for advancing the table, and means operated by the table-advancing means to control the operation of the weighing mechanism.

16. In a package-filling machine, an endless flexible traveling table having openings, a rotating drum having sprocket-teeth adapted to engage the openings in the table, and means for rotating the drum to operate the table, a filling mechanism and a weighing mechanism, and connection between the filling and weighing mechanisms operated by the weighing mechanism for advancing the table.

17. In a package-filling machine, an endless flexible table consisting of plates linked together and provided with an opening through each plate, a weighing mechanism provided with a platform adapted to be raised through the openings in the plates, means for lowering the platform through said openings, and means for advancing the table consisting of a sprocket-wheel adapted to engage said table, and connection between the sprocket-wheel and the power for rotating the sprocket-wheel.

18. In a package-filling machine, a feeding mechanism, a weighing mechanism, an endless flexible table, means for advancing the table at a variable speed consisting of gears of unequal diameters meshing in with each other and connections between the gears and the power-operated mechanism, and connections between said gears and the table.

19. In a package-filling machine, an endless flexible table provided with openings there-

through, a weighing mechanism provided with a platform adapted to be raised and lowered through the openings in the table, and means for forcing and holding down the platform after the package has been filled consisting of a plate attached to the driving-shaft and provided with a notch therein, an arm adapted to contact said plate and engage said notch, a connection between said arm and the platform of said weighing mechanism, and means for rotating said driving-shaft.

20. In a package-filling machine, an endless traveling table, means for advancing the table consisting of a sprocket-wheel engaging the table and connection between the sprocket-wheel and the power-operated mechanism, a weighing mechanism, and connection between the weighing mechanism and the power-operated mechanism for advancing the table intermittently.

21. In a package-filling machine, a feeding mechanism, a weighing mechanism, an endless flexible traveling table consisting of plates linked together and provided with grooves for determining the place where the package shall be set upon the plates while being filled.

22. In a package-filling machine, an endless flexible table consisting of plates linked together and provided with openings there-through, a groove around said openings of the diameter of the package to be filled for determining the position the package shall occupy upon the table while it is being filled, a weighing mechanism provided with a platform adapted to be raised through the openings in the table, means for lowering the platform through the openings in the table and means for advancing the table intermittently.

23. In a package-filling machine, a filling mechanism, a weighing mechanism, an endless flexible traveling table having an intermittent feed, and means connected with the weighing mechanism for controlling the intermittent feed of the table and preventing any movement of the table while the filling mechanism is operating to fill a package.

24. In a package-filling machine, a filling mechanism, a traveling table adapted to be moved intermittently, a weighing mechanism, and means connected with the weighing mechanism for controlling the filling mechanism and movements of the table consisting of a shaft 103 provided with an arm adapted to engage a ratchet-wheel on the shaft 100 and connection between the shaft 103 and the feeding mechanism.

25. In a package-filling machine, a plurality of traveling tables adapted to carry the packages, a filling mechanism, means whereby the packages upon the tables are alternately filled, and means for advancing the tables separately.

26. In a package-filling machine, a plurality of traveling tables adapted to carry the packages, a weighing mechanism, means for advancing the tables separately, and connections

between the weighing mechanism and the filling mechanism to alternately operate the latter, whereby the packages upon the tables are alternately filled.

5 27. In a package-filling machine, a plurality of traveling tables, a filling mechanism adapted to fill successively the cans placed on the tables, and means for advancing one of the tables while the filling mechanism is delivering 10 its contents into a package on another table.

15 28. In a package-filling machine, a plurality of traveling tables, each having a progressive step-by-step feed, a filling mechanism, power-operated mechanism constructed and arranged to separately advance the tables, and means included in the table-advancing means to vary the speed of the tables at each progression thereof.

20 29. In a package-filling machine, a filling mechanism, a weighing mechanism, a plurality of traveling tables adapted for intermittent and separate advancement, means connected with the weighing mechanism for operating the filling mechanism and for advancing the tables at a variable speed.

30 30. In a package-filling machine, a plurality of traveling tables, a filling mechanism adapted to fill successively the packages placed on the tables, and means for advancing one of the tables separately and carrying the filled package away from the filling mechanism while the package on another table is being filled, and connection between the means for advancing the tables and the filling mechanism.

35 31. In a package-filling machine, a plurality of traveling tables, means for intermittent and separate advancement of the tables, a filling mechanism for filling all of the packages in their order on the tables, a weighing mechanism

ism adapted to coöperate with each table, and means for operating the filling and weighing mechanism and the table conjointly.

32. In a package-filling machine, a plurality 45 of traveling tables, means for advancing each table intermittently and independent of the other tables, a filling mechanism adapted to fill packages one after another on all of the tables, and means for carrying the filled package away from the filling mechanism while a package on another table is being filled.

33. In a package-filling machine, a plurality 50 of tables, means for advancing each table intermittently and at a variable speed, a filling mechanism adapted to fill the packages one after another upon the various tables, and means connected with the filling mechanism for disengaging the means for advancing the table from the power-operated mechanism 55 while a package is being filled upon that table.

34. In a package-filling machine, a plurality 60 of traveling tables provided with openings, power-operated mechanism for intermittent and separate advancement of the tables, a filling mechanism for successively filling packages upon the tables in their order, a weighing mechanism provided with a platform for each table adapted to be raised through the openings in the tables, means for lowering 65 the platform through the openings in the table, and means for disengaging the power-operated mechanism that advances the tables to maintain each table at rest while a package thereon is being filled. 70

In testimony whereof I have signed my name to this specification in the presence of two subscribing witnesses.

DANIEL L. EUSTICE.
